ATTACHMENT PLUG

Howard C. Karst, Hanover, Pa., assignor to Bel-
den Manufacturing Company, Chicago, Ill., a
corporation of Illinois

Application November 13, 1935, Serial No. 49,599

3 Claims. (Cl. 173—361)

This invention relates to electric attachment plugs.

In the use of numerous electrical appliances, such as portable drills, etc., it frequently occurs that an appliance is used at such a point as to take up all of the slack in the attachment cord, thus transmitting a slight pull to the attachment plug which results in pulling the plug from the socket. It is thus necessary for the operator to stop work and replace the plug. Moreover, conventional plugs and sockets become loose with respect to each other and it frequently occurs that an extremely slight movement of the attachment cord will detach the plug from the socket. I am aware that prior devices have been developed with the idea of overcoming the difficulties referred to, but such prior devices involve disadvantages such as the use of a multiplicity of parts resulting in substantial production costs and the liability of mechanical derangement.

An important object of the present invention is to provide an extremely simple type of plug and socket connection wherein the parts are automatically locked in engagement with each other and wherein the parts may be readily disengaged when desired.

A further object is to provide a device of the character referred to wherein the prongs of the plug are movable inwardly to release them from the socket elements, and wherein the movement of the prongs is accomplished by exerting an inward pressure on the body of the plug.

A further object is to provide an attachment plug which completely eliminates the use of any metallic fastening elements and which may be quickly and completely assembled without the use of tools.

A further object is to provide novel means in a device of the character referred to for normally urging the plug prongs outwardly to their normal relative positions.

A further object is to provide means of the character just referred to which includes portions insertable between the ends of the cable wires to insure against short circuiting across such wires.

A further object is to provide a novel plug and socket combination of the general character referred to wherein the socket is capable of use with conventional attachment plugs.

Other objects and advantages of the invention will become apparent during the course of the following description.

In the drawing I have shown one embodiment of the invention. In this showing:

Figure 1 is a perspective view of the plug.

Figure 2 is a central vertical sectional view of the same, the prongs being shown in elevation.

Figure 3 is a similar view of an attaching socket.

Figure 4 is a detail section on line 4—4 of Figure 3, and,

Figure 5 is a detail perspective view of one of the prongs of the plug.

Referring to the drawing, the numeral 10 designates the body of the plug, and such body is formed of an integral block of resilient material such as rubber. The plug is preferably formed flat on opposite sides as at 11 and has its edge portions tapered to increase in width toward the prong end of the plug as indicated by the numeral 12. Serrated finger grip portions 13 are preferably provided at the wider end of the plug to facilitate inward pressure thereagainst for a purpose to be described.

The plug is provided with a central relatively large recess 14 opening through the larger end of the plug in a manner to be described, and at its smaller end the plug is provided with a central opening 15 to receive the usual electric cable 16. This cable is conventional and is illustrated as containing a pair of conductor wires 17 each insulated as at 18.

A pair of prong members 19 is adapted to be connected to the body of the plug. Each of these prong members is provided with an upper end portion 20 preferably having a pair of openings 21 therethrough for reception of the wires 17 in a manner to be described. Intermediate its ends, each prong member is offset inwardly to provide a shoulder 22, and the prong per se 35 23 is provided with a preferably rectangular opening 24 for a purpose to be described. At opposite edges of the opening 14, the plug is provided with substantially parallel recesses 25 each adapted to receive the extremity of the inner end 20 of 40 one of the prong members.

The prong members are arranged in the plug body in the manner shown in Figure 1, the opening 14 being provided with shoulders 26 engageable with the shoulders 22 of the prong members. 45 A resilient plug 27 is inserted in the wider end of the plug body in the manner shown in Figure 2. This plug is provided with extended portions 28 overhanging the shoulder portions of the prongs to retain them in position against the shoulders 26. Between the shoulders 26 of the adjacent end of the body, the plug 27 engages the prong members to exert an outward force thereagainst and thus retain the prong members in their proper relative positions as well as to re- 55

tain them in position in the plug body. As previously stated, the plug 27 is resilient, being preferably formed of rubber, and is insertable from the wider end of the plug by exerting endwise pressure thereagainst. The inner end of the plug 27 is provided with an extending tongue portion 29 which extends between the insulated portions 18 of the conducting wires, as shown in Figure 2. A socket suitable for use with the plug is shown in Figures 3 and 4. This socket is shown as being of the threaded type adapted for reception in threaded sockets, but it will become apparent that this type of socket is shown merely for the purpose of illustration and the socket may be of the usual wall outlet type. The socket comprises a body 30 of generally conventional size and shape having recesses or openings 31 therein to receive the prongs 23. Contact members 32 and 33 are arranged in the socket and each is provided with a perfectly rectangular tongue 34 stamped therefrom for reception in one of the prong openings 24. The tongues 34 accordingly extend partially across the prong openings 31, and the upper ends of the socket contacts are turned outwardly as at 35 to be embedded in the material of the socket body 30 and thus act as guides for the tongues 23. The contact 32 is electrically connected to the threaded shell 36 of the socket, while the contact 33 is electrically connected to the usual base contact 37.

The operation of the device is as follows:

In assembling the elements in the plug, the end of the cable 16 is first inserted through the opening 15 and pushed from the opposite end 35 of the plug. The end of each wire 17 is then inserted through one of the openings 21 from the inner face of the prong member and then through the other opening 21, in the manner shown in Figure 2. The prong members are then 40 inserted into the plug body with the extremities of the prong members inserted in the recesses 25. The plug 27 is then inserted into the end of the plug body and pressure is exerted thereagainst to force the plug into position. Both the plug 45 27 and the plug body 10 are formed of resilient rubber and the inward forcing of the plug 27 deforms this element inwardly to some extent while expanding the larger end of the plug body 10, thus facilitating the placing of the plug 27 in position.

With the parts assembled in the manner described, the upper ends of the prong members are prevented from swinging inwardly by engagement in the recesses 25. The plug 27 resiliently urges 55 the prong members outwardly, thus effectively seating the shoulders 22 on the shoulders 26, thus preventing the prongs from being pulled outwardly from the plug body. Moreover, the extending tongue 29 extends between the insulated 60 portions of the free ends of the wires 17 thus effectively preventing the short circuiting of the wires no matter how roughly the device may be handled. The plug body 10 exerts an inward pressure against the portions of the wires 17 arranged 65 outwardly of the prongs thus maintaining the wires in effective electrical engagement with the prongs without the use of the usual binding screws. While the wires 17 may be soldered to the prong members, this operation 70 also is unnecessary, since the arrangement of the parts maintains an effective electrical engagement in the manner stated. While the plug bodies may be slightly recessed to receive the portions of the wires 17 outwardly of the prong 75 members, this ordinarily is unnecessary in view

of the size of the wires employed in the conventional connecting cables 16. The rubber body 10 is readily deformable to accommodate the portions of the wires referred to.

In the use of the device it merely is necessary 5 to insert the prongs 23 in the openings 31 of the sockets, and when the parts reach the proper position with respect to each other the tongues 34 snap into the openings 24 of the prong members to effectively lock the elements together. 10 Accordingly, the appliance connected to the cable 16 may be used in any position within the length of the cable 16 and slight pulls on this cable will not cause the plug to be pulled from the socket as is true in conventional constructions. When it is desired to release the plug from the socket it merely is necessary to exert 15 an inward pressure against the serrated faces 13, the thumb and forefinger of one hand being conveniently used for this purpose. The operation referred to presses the extended ends of the prong members relatively inwardly, as suggested in dotted lines in Figure 2, thus releasing 20 the openings 24 from the tongues 34, whereupon 25 the plug may be pulled from the socket. 23

In conventional plug constructions the prong members are provided with relatively small circular openings. In constructing the present device the openings 24 are arranged nearer to the ends of the prongs than the openings in conventional prongs or are made larger and rectangular with the tongues 24 arranged in corresponding positions and similarly shaped. Accordingly a conventional plug may be used with the socket illustrated and the tongues 34 will 35 not engage in the small openings in the conventional prongs. Thus the socket may be employed with conventional plugs, but it is particularly intended for use in connection with the 40 plug illustrated.

From the foregoing it will be apparent that the present device is extremely simple in construction and embodies the use of a minimum number of parts which may be cheaply manufactured and readily assembled. No metallic 45 fastening elements such as screws, bolts or rivets are employed, and the assembly of the elements of the plug is accomplished without the use of tools. The parts will remain effectively interlocked against accidental displacement, but the 50 plug may be easily removed when desired. While the socket has been illustrated as being of the screw type, it will be obvious that it may be of any type such as a conventional wall outlet 55 socket, as previously stated.

If it becomes necessary to open the plug for any reason, the holding plug 27 may be removed by the use of a screw driver. Such implement may be alternately applied at opposite sides of the plug 27 and the latter pried out of position, 60 whereupon the prongs may be withdrawn from the plug body.

It is to be understood that the form of the invention herewith shown and described is to be taken as a preferred example of the same 65 and that various changes in the shape, size and arrangement of parts may be resorted to without departing from the spirit of the invention or the scope of the subjoined claims.

I claim:

1. A soft rubber electric connector plug comprising a main body member having its front end provided with an opening for receiving a pair of contact prongs, and an auxiliary body member intermediate said prongs, said main body 75

member being provided with rearwardly facing shoulders in opposite side walls, the prongs being respectively positioned against said opposite walls and bent intermediate their lengths to provide therein an offset, the outside of the offset portion of each of said prongs being seated respectively against the rearwardly facing shoulders of said opposite side walls, and said auxiliary body member having forwardly facing shoulders on opposite sides engaging the inner side of the offset portion of each of said prongs, whereby said auxiliary body element is locked to said plug body against endwise displacement therefrom, through the agency of said contact prongs.

2. An electric plug connector comprising a main body member, an elongated auxiliary body member, and a pair of contact prongs, said prongs and auxiliary body member being seated in a socket in said main body member with the prongs projecting forwardly from the front end of the main body member, said auxiliary body member being disposed intermediate the portions of said prongs within said body member and having a transverse dimension to engage the prongs and hold them spaced and engaged with side walls of the socket, each of said prongs having an integral shoulder cooperating with complimentary shoulders on the main and auxiliary bodies to retain the prongs and the auxiliary body in position, the minimum cross sectional width of said auxiliary body member being substantially equal to the width of said contact prongs, and said main body member having its cross sectional width materially less than its cross sectional length in the plane of the prongs and the auxiliary body member, the main and auxiliary body members being of soft rubber-like

material whereby the bodies may be compressed and the prongs thereby moved towards one another.

3. An electric plug connector comprising an elastically yieldable body having a base portion provided with a major cross sectional width and a minor cross sectional width at right angles thereto, said body being provided with a socket opening through the base and having major and minor cross sectional dimensions extending in directions corresponding to the major and minor dimensions of the base of the body, spaced contact prongs in the socket and disposed in the major cross sectional dimension of the base of the body and projecting outwardly through the entrance opening thereof and lying against walls of the socket, an elongated removable elastically yieldable auxiliary body member lying in the socket between the prongs and in contact with said prongs and holding the same spaced and in place against walls of the socket, the width of the auxiliary body at right angles to the plane of the prongs being substantially equal to the width of the prongs, each of said prongs having an integral shoulder cooperating with complimentary shoulders on the main and auxiliary bodies to retain the prongs and the auxiliary body in position, the wall portions of the body at the ends of the major dimension of the socket against which the prongs are held having thickness and bulk sufficient to hold the prongs without tearing, and the wall portions of the socket extending along the major cross sectional dimension of the socket being thin enough to permit of the socketed portion of the body being compressed by hand and the prongs thereby drawn towards one another.

HOWARD C. KARST.
